CLEANING APPARATUS

Emory B. Johnson, Gainesville, Ga.

Application September 9, 1940, Serial No. 356,055

2 Claims. (Cl. 15—106)

This invention relates to cleaning apparatus, and its general object is to provide an apparatus that is primarily designed for use in multiple machine spinning rooms of textile mills for simultaneously cleaning the floor of the alleys between the spinning frames or machines and the base or spindle rails of the machines on the opposite sides of the alleys, the apparatus including both floor and rail brushes for sweeping lint, dirt and the like, from the floor and rails, as it is pushed through the alleys, and the apparatus is adjustable for alleys of various widths and rails of various heights.

A further object is to provide a wheeled and handled cleaning apparatus that includes pivoted rail brush carrying means controlled by the handles, to allow for free passage of the apparatus about machine operators and workers in the alleys, and the floor brushes are likewise pivoted or hinged, as well as connected to the handles to be raised thereby for passage over piles of swept up material, and to facilitate removing lint or the like from the brushes.

Another object is to provide a cleaning apparatus of the character set forth, that is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a side elevation of the apparatus which forms the subject matter of the present invention.

Figure 2 is a top plan view thereof.

Figure 3 is a front view.

Figure 4 is a sectional view taken approximately on line 4—4 of Figure 1, looking in the direction of the arrows.

Figure 5 is a sectional view taken approximately on line 5—5 of Figure 2, looking in the direction of the arrows.

Figure 6 is a sectional view taken approximately on line 6—6 of Figure 3, looking in the direction of the arrows.

Referring to the drawing in detail, it will be noted that my cleaning apparatus includes an upright rectangular body frame in the form shown, and the frame is made up of upper and

lower bar members 1 and 2 and upright side members 3 and 4, the upper and lower members each including a pair of intermediate sections 5 and 6 and end sections 7 and 8.

The intermediate sections have reduced end portions and the inner portions are slotted and disposed in overlapped relation, with bolts of bolt and nut connections 9 extending through the slots for connecting the intermediate sections together as well as to allow adjustment thereof for adjusting the length of the frame to fit alleys of various widths, as will be apparent, upon inspection of Figures 2 and 5.

The inner end portions of the end sections are likewise reduced and disposed in overlapped relation with respect to the outer end portions of the intermediate sections, as well as connected thereto by bolt and nut connections 10 for pivotal movement of the end sections on the bolts thereof, for a purpose which will be later described.

The upper ends of the side members are fixed to the outer ends of the end sections of the upper member 1 and the joint is reinforced by angle brackets 11, while the outer ends of the end sections of the lower member 2 are connected to the lower portions of the side members 3 and 4 by screws 12 having their shanks slidably mounted in slots 13 extending longitudinally of the side members from adjacent the lower ends thereof, as clearly shown in Figures 1 and 4. A pair of intermediate uprights including upper and lower sections 14 and 15 are secured to and disposed between the upper and lower members 1 and 2 and the sections of each of the uprights have reduced inner ends disposed in overlapped relation, with longitudinal slots 16 in the reduced portions for receiving the bolts of bolt and nut connections 17. By that construction, together with the slidable connection of the lower member 2 with the side members 3 and 4, it will be obvious that the frame can be adjusted to various heights and held accordingly by the bolt and nut connections 17.

Secured to the intermediate sections of the lower member 2 is a pair of caster wheels 18 and pivotally connected to the side members by bolt and nut connections 19 or the like, are the reduced inner ends of handles 20 extending rearwardly from the frame, and the outer end portions of the handles are preferably rounded as at 21 to provide a smooth gripping surface, as will be apparent. Brace members 22 are provided for the handles and have one of their ends connected thereto by hinges 23, while the opposite end portions are reduced and have longitudinally

extending slots 24 therein for receiving the bolts of bolt and nut connections 25 for connecting the brace members to the side members adjacent to the upper ends thereof, as best shown in Figure 1. The brace members are slidably mounted on the bolts of the latter connections, so as to allow free pivotal movement of the handles, as will be apparent.

Fixed to the front and rear faces of the side members are the heads 26 of pairs of elongated brushes 27, which are of a length co-extensive with the height of the side members and extend laterally thereof, so that a space is provided between the brushes of each pair, as best shown in Figure 2. The brushes 27 are for the purpose of sweeping lint and foreign matter from the base or spindle rails of the spinning frames, as the apparatus is pushed through the alleys between the machines, and due to the fact that the frame is adjustable as to height, the brushes are capable of reaching the machine rails of any height. However, it will be understood that the machine rails are horizontally disposed, and it might be mentioned that the spaces between the brushes allow for the passage of lint and the like from the rails to the floor.

The floor brushes which are two in number in the form shown, are indicated by the reference numeral 28 and are arranged in end to end relation to extend throughout the length of the frame. Fixed to the heads of the floor brushes 28 are one of the ends of arms 29 that have their opposite ends connected to the intermediate sections of the lower frame member 2 by hinges 33, for the brushes to extend rearwardly from the frame, and they are preferably connected to the handles by flexible elements 31, so that they can be raised by the handles, for passage over piles of swept up material, as will be apparent. The hinged connection of the brushes 28 likewise materially facilitate removing lint and the like therefrom.

From the foregoing description and the disclosure in the drawing, it will be obvious that I have provided a cleaning apparatus that is extremely efficient for the purpose of cleaning the rails of spinning machines and the floors of the alleys between the machines, and as the apparatus is pushed through the alleys, the rail brushes can be swung on the pivots of the end sections to allow passage of the apparatus about spinners or operators in the alleys, thus it will be seen that the machine rails and floors can be swept with

minimum effort by the use of my apparatus, without disturbing the operators.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A cleaning apparatus comprising a wheeled upright body frame, upright brushing means secured to and extending laterally from the frame, means included in the frame for adjusting the height of the brushing means, pivoted means included in the frame and carrying the brushing means for swinging movement of the latter, floor engaging brushing means pivotally secured to and extending rearwardly from the frame, handles pivotally and slidably associated with said pivoted means for swinging the upright brushing means, and flexible means connecting the floor engaging brushing means to the handles.

2. A cleaning apparatus comprising an upright body frame including upper and lower bar members, upright side members fixed to the ends of the upper bar member and slidably connected to the lower bar member for adjusting the height of the side members, adjustable intermediate upright members secured to the upper and lower members and for holding the side members in adjusted positions, said upper and lower members being adjustable lengthwise for adjusting the length of the frame, pivoted end sections included in the upper and lower members for swinging movement of the side members, a pair of spaced brushes secured to each of the side members throughout the height thereof and extending laterally therefrom, a pair of floor engaging brushes hingedly connected to the lower member for swinging movement in a vertical plane, caster wheels secured to the lower member, handles pivotally connected to the side members for swinging the first brushes on the pivots of said sections, bracing means for the handles and hingedly connected thereto, said bracing means being slidably connected to the side members, and flexible means connecting the floor engaging brushes to the handles.

EMORY B. JOHNSON.
